UNITED STATES PATENT OFFICE.

ARTHUR KIRKHAM, OF BOLTON, ENGLAND.

FORCE-FEED LUBRICATOR.

1,073,142.

Specification of Letters Patent. Patented Sept. 16, 1913.

Application filed November 27, 1908, Serial No. 464,595. Renewed July 8, 1913. Serial No. 777,961.

To all whom it may concern:

Be it known that I, ARTHUR KIRKHAM, a subject of the King of Great Britain, and resident of No. 48 Third avenue, Ferns Estate, Bolton, in the county of Lancaster, England, have invented a new and useful Improvement in Force-Feed Lubricators, of which the following description, together with the accompanying sheets of drawings, is a specification.

The invention relates to lubricators of the type in which the oil is positively forced in small quantities to the different parts of an engine against the internal pressure of steam in such engine. In this type of lubricator as usually heretofore constructed, considerable difficulty has been encountered whenever any of the lubricating passages or the valves have had to be repaired or cleaned.

One of the objects of my present invention is to provide a lubricator of the character described having the several parts or connections so constructed and arranged that the valves and the passages for the lubricant may be easily cleaned or repaired.

Another object of the invention is to provide a lubricator of the character described in which the lubricant, on its way through transparent portions of its course, will not adhere to any part of said transparent portions.

Further objects of the invention are to provide improvements in lubricators of this character which especially enable it to be used to cause a very slight supply of lubricant at each impulse of the engine with which the lubricator is connected, such small supply being effected in the form of globules which are fed to the cylinder at the same time that the admission valves are opened for the supply of steam to the cylinder.

To attain these objects, the invention consists in the construction and combination of parts substantially as hereinafter described and claimed.

Of the accompanying drawings, Figure 1 is an elevation of a lubricator constructed according to my invention. Fig. 2 represents a section on line A—B of Fig. 1. Fig. 3 represents a section on line C—D of Fig. 2, other portions being broken out to show the structure at the top of the lubricant reservoir. Fig. 4 represents a section on line E—F of Fig. 2, looking in the direction of the arrow a'. Fig. 5 is a detail sectional view hereinafter referred to. Fig. 6 is a

vertical section of the sight feed tube and its coating parts, and illustrates a modification hereinafter referred to. Fig. 7 represents a section on line G—H of Fig. 6. Fig. 8 represents a horizontal section through the base of the lubricator.

Similar reference characters indicate the same or similar parts in all of the views.

A central chamber a is provided in the base d, an oil reservoir b being provided above said central chamber by means of a glass cylinder c which is mounted upon the base, suitable packing 22 being preferably employed at the ends of said cylinder.

The top of the apparatus is formed by a cover e having a removable lid 24 by means of which the oil reservoir may be filled. Preferably a basket 25 (see dotted lines, Fig. 3) is provided in the cover e, said basket being formed to receive and retain any sediment deposited by the lubricant.

A series of glass tubes 8 are mounted on the base around the cylinder c, packing 10 being interposed between their lower ends and the top of said base, and packing 11, being interposed between their upper ends and the lower ends of tubes w, which are adjustably mounted in the cover e. Adjustably mounted in each tube w is a plug 85 screw 21 for a pendent wire 20, the lower end of which extends into the nipple z carried by the upper end of a plug 17. I prefer the construction shown in Fig. 4, in which a single wire 20 is employed in each tube, but may employ a greater number of wires as indicated in Figs. 6 and 7, in which three wires 20 depend from the portion 210 of a plug 200 mounted in the tube w.

The lower portion of the base d is formed with apertures or passages f, f', f², f³, as best shown by comparing the dotted line representation in Fig. 2 with Fig. 4. There are as many such passages as there are tubes 8 and different parts of the engine to be lubricated. I will proceed to describe the passages which communicate with the passage f'. The passage f' connects with the lower end of a vertical passage g' in the base, the upper portion of which is connected by an inclined passage m' with the lower end of another vertical passage n', the upper portion of the latter communicating by an inclined passage u' with an aperture in the plug 17 which connects with the lower end of a vertical passage v' in said plug. In the passage g' are spherical valves

3, 3^a; in the passage n' are spherical valves 4, 4^a; and in the passage v' is a spherical valve 7. (See Fig. 4.) An escape duct 27 from the passage m' has its outer end closed by a plug 27^a (see Figs. 1 and 3).

Connecting with the lower end of the passage n' (see Fig. 3) is a horizontal passage p' in the outer end of which is set a screw plug 12, the inner end being formed as 10 a barrel and containing a plunger q' .

The above passages and connections having the prime (') mark as an exponent are duplicated as to the other passages constituting the entire series of four, said other 15 passages being indicated by the exponents 2 and 3 or by similar letters without exponents. The passages described are all formed in the base and connect with each other in such manner that they are easily 20 formed by means of a drill working from the outside of the base toward the center, or in an inclined direction, or from the upper surface downward. Those passages which are drilled in from the outside are closed by 25 stopper screws h , h' , h^2 , h^3 . The vertical passages are formed with shoulders to form valve seats, one of said shoulders being indicated at k in Fig. 4.

As shown by comparing Figs. 2 and 3, the 30 plungers are arranged in pairs, opposite each other, their inner ends having heads on opposite sides of arms r or r' depending from a shaft s mounted transversely of the central chamber a , the outer end s' of the 35 shaft passing through a gland s^2 and being formed to have connected thereto any device by means of which said shaft can be rocked. In practice, the connections will be such that the shaft is rocked at each impulse of 40 the engine, so that each of the plungers will be actuated first in one direction and then in the other, springs t , t' , t^2 , t^3 being interposed between the heads at the inner ends 45 of the plungers and the bearings or barrels in which the plungers work. Preferably ball bearings 5 are interposed between the plunger heads and the shaft arms. When the shaft rocks in a direction so as to permit either spring to retract a plunger, oil is 50 drawn in behind the plunger, and on the return movement of the shaft the plunger is positively actuated to force the oil toward the part to be lubricated. Referring to the 55 passages having the reference letters indicated by a prime (') mark (see Figs. 3 and 4), the movement of the plunger q' , under the influence of its spring, will draw oil through passages f' , g' , m' past the check valves 3 and 3^a. On the return and positive 60 movement of the plunger, the small quantity of oil so drawn in will be forced upwardly through the passage n' past the check valves 4^a and 4, through the passage u' into the passage in the plug 17 and upwardly 65 through the passage v' past the check valve

7. The check valves 7, 4, and 4^a prevent any possibility of water being drawn backwardly.

The tops of the vertical passages such as those shown at g' , n' , are closed by caps 13, the latter being held down in pairs by a cross piece 14 secured by a central screw 15, and therefore any connected series of said passages can be quickly gained access to for cleaning by removing the screw 15 and lifting the piece 14 and caps 13. This can be done without stopping the operation of the other portions of the lubricator. 75

As is usual with this type of lubricator, the glass tubes 8 contain water. The drops of oil forced upwardly through the passages in the plugs 17 simply follow along the wires 20, without liability of contact with the inner walls of the glass tubes, and finally escape through the outlet z , (see Fig. 5), said outlet having a check valve 12^a and connecting with a nipple y which in turn will be connected by any suitable pipe to the part to be lubricated. 80

By the structure illustrated, a small portion of oil may be admitted to the cylinder of the engine at the same time that steam passes the admission valves thereof, so that at every stroke of the piston a quantity of oil, sufficient to lubricate it for that stroke, 95 may be supplied to the cylinder of the engine. The quantity of oil delivered may be separately regulated and fixed for each feed tube from the lubricator, this being done by means of the adjusting plugs 27^a which may be opened more or less to permit some of the oil drawn in by the plunger to be forced back into the central chamber of the lubricator, each duct 27 connecting an inclined passage in the base with the central chamber a . Any one of the ducts 27 may be fully 100 opened by manipulating its screw or plug 27^a, in order to allow all the oil discharging from the cylinder by the operation of its piston, to be returned to the central chamber 105 of the lubricator. When all the oil is returned to said central chamber, any one of the glass tubes 8 may be removed for any purpose desired. Testing, or inspecting, or repairing of one set of passages may be performed without interfering with the connections and operation of the other sets of passages by simply removing the caps 13. Owing to the pump plungers working horizontally in the lowest part of the oil reservoir, there can be no danger of the oil having 110 air mixed with it by the operation of the plungers. 115

The nipple z is connected to the hollow plug 17 and the wire 20, which is fixed to the 125 plug 21, enters and projects closely within said nipple z , thus allowing each globule of oil discharged by the operation of one or the other of the plungers of the lubricator, to pass through said nipple z and around 130

the wire 20, to which it adheres, following up said wire, without contact with the inner wall of the glass, until it reaches the plug 21. Since the wire 20 enters a short distance 5 within the opening of nipple z, there is no opportunity for the globule to escape without adhering to the wire, as would be the case if the end of the wire were above the top of the nipple z.

10 I claim:

1. In lubricating apparatus of the class described, a central holder comprising glass sides and a metal base, the latter having openings extending to its outer wall and having also substantially vertical passages intersecting said openings, valves in said passages and plungers in said openings, plugs closing the outer ends of said openings, means for actuating the plungers, and 15 a series of sight feed tubes around the central holder.

2. In lubricating apparatus of the class described, a base piece having valved passages, a shaft mounted in the base piece, arms 20 on said shaft, plungers mounted in said passages and operatively engaged by opposite sides of said arms, and springs for actuating said plungers in opposition to said arms.

3. A lubricator of the character described, 25 comprising a base having a central chamber, a shaft extending transversely of said central chamber and having arms, an oil reservoir mounted on the base above said chamber, a series of tubes mounted on the base 30 around said reservoir, said base having valved passages connecting its central chamber with said tubes and having also barrels communicating with said passages, plungers mounted in said barrels, and springs for 35

holding the plungers in contact with the 40 arms of the shaft.

4. A lubricator of the character described, comprising a base having a central chamber, an oil reservoir mounted on the base above 45 said chamber, a series of tubes mounted on the base around said reservoir, said base having valved passages connecting its central chamber with said tubes and having also barrels communicating with said passages, controllable by-pass connections between 50 said passages and central chamber to enable the quantity of feed for each set of passages to be regulated, plungers mounted in said barrels, and means located in the said central chamber for actuating said plungers. 55

5. A lubricator of the character described, comprising a base having a central chamber, an oil reservoir mounted on the base above 60 said chamber, a series of tubes mounted on the base around said reservoir, said base having valved passages connecting its central chamber with said tubes and having also barrels communicating with said passages, plungers mounted in said barrels, removable 65 plugs at the ends of the valved portions of said passages, said removable plugs being arranged in pairs, a single bar bearing on the two plugs of each pair, a screw for holding the said bar against the plugs to hold them in place, and means located in the said central chamber for actuating said plungers. 70

In testimony whereof I have hereunto affixed my signature in presence of two witnesses.

ARTHUR KIRKHAM.
